(57) **CLAIM**

The ornamental design for a display screen with graphical user interface, as shown and described.

DESCRIPTION

The application also incorporates by reference the entire contents of U.S. patent applications Ser. Nos. 13/724,163 filed on Dec. 21, 2012 and 14/228,723 filed on Mar. 28, 2014.

The sole FIGURE is a front view of a display screen with graphical user interface showing our new design.

The outermost broken line showing of a display screen and the other broken lines showing elements of the graphical user interface illustrate portions of the article and do not form part of the claimed design.
